UNITED STATES PATENT OFFICE.

THOMAS M. HOUSE, OF WELDON, NORTH CAROLINA.

CLOTHES-PRESSING TOOL.

984,673.

Specification of Letters Patent. Patented Feb. 21, 1911.

Application filed January 12, 1910. Serial No. 537,726.

To all whom it may concern:

Be it known that I, THOMAS M. HOUSE, a citizen of the United States, residing at Weldon, in the county of Halifax and State 5 of North Carolina, have invented certain new and useful Improvements in Clothes-Pressing Tools, of which the following is a specification, reference being had to the accompanying drawings.

10 This invention relates to improvements in self-heating pressing irons or tools, and while it may be variously embodied for different purposes, it is more especially adapted for creasing trousers, coat lapels and 15 other portions of wearing apparel without removing them from the person, the tool being especially adapted for use in barber shops, shoe shining parlors and tailoring establishments.

20 One object of the invention is to provide a simple and practical device of this character in the form of a pair of pliers or tongs so that it may be conveniently manipulated.

25 Other objects of the invention are to provide a device of this character with improved means for mounting the pressing members, and improved means for electrically heating them.

With the above and other objects in view, 30 the invention consists of the novel construction, combination and arrangement of parts, hereinafter fully described and claimed, and illustrated in the accompanying drawings in which:—

35 Figure 1 is a perspective view of my improved clothes pressing iron or tool; Fig. 2 is a sectional view through the same; Fig. 3 is a longitudinal section through one of the pressing members or heads taken on the 40 plane indicated by the line 3—3 in Fig. 2; Fig. 4 is a plan view partly in section of one of the pressing members or heads with its outer cover plate removed; Fig. 5 is a perspective view of the cover plate of one 45 of the pressing members or heads; Fig. 6 is a perspective view of the core of one of the heating coils; Fig. 7 is a detail section taken on the plane indicated by the line 7—7 in Fig. 2; and Fig. 8 is a detail end 50 view showing the pressing members or heads provided with corrugated opposing faces.

The invention comprises two opposing pressing members or heads 1, either or both of which may carry self-heating means, and

either or both of which may be pivotally 55 mounted to cause the two members to adapt themselves to the object placed between them. These members are carried by hand levers 2 preferably crossed intermediate their ends and united by a pivot 3, the members or heads 1 being carried by the outer ends of said levers and the inner ends of the latter being formed with finger or hand loops 4 whereby the device resembles a pair of tongs or pliers with the members 1 forming the jaws thereof. When the members or heads 1 are of substantially rectangular form as shown, the outer ends of the levers 2 are curved outwardly in opposite directions as shown at 5 so as to receive said 60 members, the pivotal connection of the latter being preferably effected by forming the ends 5 of the levers with transverse tubular projections or arms 6 which receive transverse pivots 7 having projecting ends rotatable in bearing lugs or brackets 8 formed integral with or attached to the members or heads 1. By 65 mounting one or both of the members 1 on such a transverse pivot it will be seen that the two members will adapt themselves to 70 the shape of the object placed between them and thereby enable such object to be more effectively pressed.

In order to maintain the pressing members or heads 1 normally in substantially 85 parallel relation, I preferably provide leaf springs 9 and stops 10. The springs 9 have their inner ends secured at 11 to the curved portions 5 of the levers and their free ends bear against the outer faces of the members 90 or heads 1 so as to press them against the stop lugs 10, the latter being formed preferably integral with the outer extremities of the levers and on the transverse portions or arms 6, as shown.

95 The pressing members or heads 1 may be of any desired shape and construction, and their opposing operative faces may be flat, curved or of irregular shape, and they may be either smooth or roughened. However, 100 when the device is to be used for creasing trousers, pressing coat lapels or the like, I preferably make the co-acting or opposing faces of the members or heads flat and roughen them by nurling 12. I wish it 105 understood, however, that any other roughened finish may be provided on the active faces of the pressing members and that, if

desired, said faces may be corrugated as shown at 13 in Fig. 8, or otherwise shaped according to the use which the iron is to serve.

5 While any suitable means may be provided for heating the pressing members or heads 1, I preferably employ electrical coils 14. These coils are formed of wire wrapped around a metal core 15, the latter being of 10 substantially rectangular shape and having insulating strips 16 folded around its longitudinal edges and adapted to support the wire coils 14, which latter pass transversely around the core, as shown in Fig. 4. The 15 core 15 serves not only as a support for the coil but also as a heat-retaining member, and while it may be of any shape and construction it is preferably formed from a substantially rectangular metal plate and has 20 rounded, longitudinal edges 17, recessed side faces 18 and openings 19, the latter reducing its weight so that the tool will not be too heavy to be conveniently manipulated. The core and its coil 14 is surrounded by insulating strips or plates 20 which insulate it from the pressing member or head in which it is positioned and which line the opening or cavity in such member or head. While 25 as above stated said members or heads may 30 be of any desired shape and construction, they are here shown as in the form of hollow, rectangular boxes each consisting of a body portion 21, and a removable cover plate 22. The body 21 is closed and has its 35 outer face open to receive the cover plate 22 which latter retains the coil and its core in the cavity or chamber 23 of said body. In order to secure the plate 22 in position and at the same time permit of its ready removal 40 for repair purposes, the ends of said plate are adapted to rest on shoulders 24 formed in the end walls of the body 21, and one end of said cover plate is formed with a longitudinally projecting tongue 25 to enter a recess or seat 26 formed in the adjacent end 45 wall of the body. The other end of said cover plate has a transverse opening to receive a fastening screw 27, which latter enters a threaded socket 28 formed in one of 50 the shoulders 24. It will be seen that when the screw 27 is removed, the cover plate may be slipped out of the body of the heating member or head. If desired I may place beneath the cover plate one or more sheets 55 29 of asbestos or other material which is a non-conductor of heat in order to prevent the radiation of heat through the cover plate to the levers. It will be noted that the knurled operative faces 12 of the heating 60 members are formed integral with the boxes or casings 21, and that the pivot lugs or brackets 8 are formed integral with the cover plates, such construction being the preferable form of constructing the device. The 65 terminals of the resistance or heating coil 14

is connected to two binding posts or screws 30 arranged in and insulated from the inner longitudinal walls of the bodies 21 of the heating members. Each of these binding posts 30 consists of a screw arranged in the 70 tubular boss or enlargement 31 formed on the body 21 and insulated therefrom by a tubular insulating member or sleeve 32 arranged in said boss. The head of the screw is arranged within the body 1 and is in electrical contact with the coil 14, and on the outer threaded end of the screw are a pair of milled nuts 33, 34, beneath which are clamped one of the terminals of electric circuit conductors. These circuit conductors 80 are arranged in the usual insulated cord or cable 35, the end of which has insulated branches 36 terminating in apertured contact plates or washers 37, which latter are arranged between the nuts 33, 34. 85

For the purpose of guiding the conducting cable or cord 35 and preventing it from becoming twisted around the hand levers, two guides 38, 39 are provided for it. The guide 38 is in the form of an apertured lug or projection formed integral with and on the inner face of one of the hand loops 4, the portion of such hand loop opposite said lug 38 being channeled or grooved for the reception of the conductor. The other guide 39 is secured to or formed upon one end of the pivot 3 for the levers, which pivot is preferably in the form of a bolt and has the guide 39 formed integral with its head. This guide consists of a transverse enlargement formed 90 on the head of the pivot bolt 3 and provided with a transverse bore 40 and an intersecting longitudinal slit 41 which extends from one end to a point adjacent to the other end of said enlargement. The bore 40 is adapted 95 to receive the conducting cord 35, an insulating sleeve 42 being arranged within said bore and around the conductor, and the latter is adapted to be securely clamped in said bore by means of a screw 43 passed through 100 an opening in the outer portion of the slit end of said enlargement and into a screw threaded opening 44 formed in the inner or base portion of said enlargement, as clearly 105 shown in Fig. 7 of the drawings. It will be seen that the member 39 not only serves 110 as a guide but also as a clamp for preventing the conducting cord from being pulled off of the tool. 115

From the foregoing it will be seen that 120 the invention provides an exceedingly efficient portable pressing iron, and one which will be very useful in barber shops, shoe shining parlors, dressmaking, millinery and tailoring establishments, in the home, and in fact any place where clothes, cloth or other material is to be pressed with a heated iron. The peculiar manner of mounting the heating members or heads on the hand levers renders it exceedingly effective for 130 125 130

creasing trousers, coat lapels and other wearing apparel without removing the same from the person.

I have found in practice that the device 5 is exceedingly effective for the purposes intended and the embodiment illustrated may be effectively used in barber shops, shoe shining parlors and the like, for pressing trousers, pocket and coat lapels without removing 10 the garment from the customer, and while the latter is getting his shoes shined. By heating the pressing heads or members electrically an even temperature is maintained so that there will be no danger of burning 15 the garment, the iron may be continuously used and there will be no dirt or danger of soiling the object that is pressed.

While the preferred embodiment of the invention has been shown and described in 20 detail, it will be understood that I do not wish to be limited to the precise construction set forth, since various changes in the form, proportion and arrangement of parts, and in the details of construction, may be 25 resorted to within the spirit and scope of the invention.

Having thus described the invention what is claimed is:

1. An electrically heated pressing tool 30 comprising a pair of pivotally connected hand levers, opposing pressing heads carried by the outer ends of said levers and having flat, roughened, opposing surfaces to receive a portion of a garment between them, a 35 transverse pivot uniting one of said heads to its lever whereby said head may be swung longitudinally of the lever and angularly with respect to the other head, a spring bearing against said pivotally mounted head and 40 carried by the lever which supports said head, and means for electrically heating one of said heads.

2. An electrically heated pressing tool comprising pivotally connected hand levers, 45 opposing pressing heads carried by the outer ends of the said levers, a pivot connecting one of said heads to its lever, a spring bearing against said pivotally mounted head and carried by the lever which supports 50 said head, and means for electrically heating one of said heads.

3. An electrically heated pressing tool comprising pivotally connected hand levers, opposing pressing heads carried by the outer 55 ends of said levers, a pivot connecting one of said heads to its lever, a stop to limit the swinging movement of said pivotally mounted head, said stop being carried by the lever which supports said head, a spring carried 60 by the last mentioned lever and bearing against the pivotally mounted head to maintain it in contact with said stop, and means for electrically heating one of said heads.

4. An electrically heated pressing tool 65 comprising a pair of pivotally connected

hand levers, opposing pressing heads carried by the outer ends of said levers and pivotally connected thereto whereby said heads may swing angularly with respect to each other and adapt themselves to the object 70 placed between them, the opposing pressing faces of said heads being roughened, stops carried by said levers and adapted to be engaged by said heads whereby the swinging movement of the latter is limited, positioning 75 springs carried by said levers and bearing against said heads to hold them in contact with their stops and means for electrically heating one of said heads.

5. An electrically heated pressing tool, 80 comprising a pair of hand levers, a pivot uniting said levers, and formed at one end with a clamp, a guide on the handle end of one of said levers, a pair of opposing pressing heads pivotally mounted on the outer 85 ends of said levers, stops on said levers to limit the swinging movement of said heads, springs carried by said levers to bear against the heads and maintain them in contact with the stops, electric heating means 90 in said pressing heads, and an electric cable passed through said eye and said clamp and having flexible branch conductors connected to the electrical heating means in said heads.

6. An electrically heated pressing tool 95 comprising a pair of pivotally connected hand levers, opposing pressing heads carried by the outer ends of said levers, and provided with flat opposing faces to receive a portion of a garment between them, transverse 100 pivots uniting said heads to said levers whereby the opposing faces of said heads may be swung angularly with respect to each other to adapt themselves to the garment placed between them, means carried by said 105 levers to position the flat opposing faces of the pressing heads in substantially parallel relation, and means for electrically heating one of said heads.

7. An electrically heated pressing tool 110 comprising a pair of pivotally connected hand levers, opposing pressing heads carried by the outer ends of said levers, and provided with flat opposing faces to receive a portion of a garment between them, transverse 115 pivots uniting said heads to said levers whereby the opposing flat faces of said heads may be swung angularly with respect to each other to adapt themselves to the garment placed between them, stops carried by 120 said levers to limit the swinging movement of said heads, springs carried by said levers to engage said heads and yieldably maintain them in contact with said stops, and means for electrically heating one of 125 said heads.

8. An electrically heated pressing tool comprising a pair of pivotally connected levers, the latter being crossed and having finger pieces at their inner ends and their 130

outer ends curved outwardly in opposite directions and formed with laterally projecting studs and centrally arranged stop lugs, opposing pressing heads having on 5 their outer faces spaced bearing brackets, to receive said studs between them and having flat opposing inner faces provided with roughened surfaces, transverse pivots uniting said studs and bearing brackets, springs 10 fixed to the curved ends of said levers and

bearing against said heads to maintain them in contact with said stop lugs, and means for electrically heating one of said heads.

In testimony whereof I hereunto affix my signature in the presence of two witnesses. 15
